CLAIM

The ornamental design for a toilet brush & holder therefor, as shown.

DESCRIPTION

FIG. 1 is a perspective view of a toilet brush and holder therefor, showing my new design and shown with the brush and holder separated;

FIG. 2 is a perspective view thereof, shown with the brush inserted in the holder;

FIG. 3 is a side elevational view thereof;

FIG. 4 is a front elevational view thereof;

FIG. 5 is a top plan view thereof; and

FIG. 6 is a bottom plan view thereof.
